UNITED STATES PATENT OFFICE.

SAMUEL HALBERG, OF BROOKLYN, NEW YORK.

SEWING-MACHINE ATTACHMENT.

Application filed April 14, 1926. Serial No. 101,994.

The present invention is concerned with the provision of an attachment for sewing machines, which is primarily adapted to facilitate the feeding and applying of a binding tape or strip. More specifically the invention involves the provision of a holder for a roll of tape, means for feeding the tape under the presser foot, and a gauge plate for the tape and garment which will maintain the edges of the tape and the material to which it is being sewed, in proper alignment.

The invention also includes in combination with the gauge plate, a tape guiding and severing member, so that the tape may be readily severed at any point.

Objects of the invention are to provide an attachment of this character which will save considerable time and labor in the operation of applying a binding tape, and an attachment which may be readily applied to a conventional type of sewing machine without requiring any structural changes in the machine itself.

Further objects of the invention are to provide an attachment of this character which will be of simple, practical construction, which will be rugged and durable in use, which may be readily applied to or removed from a machine by an unskilled workman, and an attachment which may be manufactured with comparative economy.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a perspective view of a sewing machine showing my improved attachment in applied position.

Fig. 2 is a vertical sectional view through the tape holder.

Fig. 3 is a transverse sectional detail through the plate which mounts the tape holder.

Fig. 4 is a sectional plan view of the gauge plate and associated mechanism.

Fig. 5 is a transverse sectional view on the line 5—5 of Fig. 4.

Fig. 6 is a sectional view on the line 6—6 of Fig. 4.

The tape feed and gauging attachment of

the present invention may be applied to various types of sewing machines, although I have elected to show an embodiment of the invention in which the device is peculiarly suited for application to a small chain stitch machine of the Singer type.

In the drawings 10 represents the bed of the machine, and 11 the usual arm mounting a head 12. The needle 13 works through the usual presser foot 14 and through a needle plate 15. I have used the reference character 16 to designate a piece of material to which a binding strip is to be applied, and the numeral 17 to represent the strip or tape.

As thus far described the machine is entirely conventional, the present invention being more particularly concerned with the provision of means for mounting the tape, means for guiding the aligned edges of the tape and material 16 under the needle, and means for severing the tape at any point.

The tape holder includes a pair of vertically disposed spring plates 18, the lower ends of which are preferably integrally connected by a bridge 19 and the upper ends of which are secured together by a bolt 20 encircled by a spacer 21. A tensioning screw 22 connecting the intermediate portions of the plates 18 serves as a hub for a floating roll 17^a of tape 17, and by adjusting the screw 22 any desired tension may be applied to the roller.

The tape holder is mounted upon a plate 23 secured to the forward end of the arm 11, and to the head 12 of the machine. Preferably the plate 23 is secured by a screw 24 to the machine head, and the rear end of the plate 23 receives the upwardly presented threaded ends 25 of a U-bolt or stirrup 26 straddling the arm 11. Nuts 27 on the ends of the member 25 co-operate with the screw 24 to effectively lock the plate 23 against movement in any direction, so that the plate 23 will afford a rigid supporting means for the plates 18.

Plate 23 is formed with a laterally disposed arm 28 slightly channelled to receive the bridge 19 and bolted thereto as at 29. One end of the bridge member 19 may be struck downwardly and bent around under the arm 28 as indicated at 30 to further strengthen the connection between the plates 18 and the plate 21.

Depending from a laterally offset extension of the plate 23 is a channel guide 31

through which the strip 17 is guided from the roll to the needle.

To properly maintain the edge to edge alignment of the binding strip 17 and the material 16, I secure a gauge plate 32 directly upon the needle plate 15 of the machine. This gauge plate may be conveniently secured by binding screw 33, and is formed with an upstanding guiding flange 34 at its free end against which the edges of the material 16 and strip 17 abut as they are passed under the needle. To prevent pivotal movement of the gauge plate 32 about the screw 33, the rear end of the gauge plate is preferably turned downwardly as at 35 and recessed as at 36 to straddle the convex upper face of the machine bed 10.

In order to permit severance of the strip 17 at any point, I mount a knife 37 on the gauge plate, this knife passing under a strap 38 on the plate and being held by screw 39. The cutting end of the knife projects through an opening 40 in the flange 34 and extends over the tape 17. Thus, the knife end serves as a guide for the tape and is in convenient position to cut the tape by having the same moved against the cutting edges thereof at the will of the operator.

It is believed that the operation of the device will be evident from the foregoing description, but it may be noted briefly that the positioning of the plate 23 on the machine automatically positions the tape holder and the tape guide 31. A roll of tape is secured in the holder and the screw 22 adjusted to properly tension the tape. The end of the tape is threaded through the guide 31 and under the presser foot 14. The material 16 together with the tape end is then held against the flange 34 of the gauge plate while the machine is running, so that the common inconvenience of attempting to

properly gauge the alignment of the tape and the material is done away with. The tape may be severed at any time by simply manually grasping it and swinging it against the cutting edge 37.

Various changes and alterations might be made in the general form and arrangement of parts described without departing from the invention. Hence I do not wish to limit myself to the details set forth, but shall consider myself at liberty to make such changes and alterations as fairly fall within the spirit and scope of the appended claims.

I claim:

1. An attachment for sewing machines comprising a tape roll holder adapted to be supported on the arm of the machine, said roll holder including a pair of vertically disposed spring plates and a tensioning screw connecting them, said screw serving as a hub for a floating tape roll frictionally gripped between the plates.

2. In an attachment for sewing machines, a tape roll holder including a pair of vertical spring plates connected by a bridging piece at their lower ends, and a supporting plate including a lateral extension around which a portion of the bridging piece is bent.

3. An attachment as set forth in claim 2, and wherein the extension is channelled to receive the bridging piece.

4. In an attachment for sewing machines, a tape roll holder supporting plate including an extension adapted to be secured to the head of the machine, a tape roll holder mounted thereon, a stirrup for encircling the arm of the machine having its ends secured to the plate, and a lateral depending channelled tape guiding extension on the plate through which the end of the tape is adapted to be threaded.

SAMUEL HALBERG.
